ROTARY STEAM ENGINE.

No. 330,347.

Patented Nov. 10, 1885.

UNITED STATES PATENT OFFICE.

WILLIAM O. OWEN, JR., OF LYNCHBURG, VIRGINIA.

ROTARY STEAM-ENGINE.

SPECIFICATION forming part of Letters Patent No. 330,347, dated November 10, 1885.

Application filed September 10, 1885. Serial No. 176,685. (No model.)

To all whom it may concern:

Be it known that I, WILLIAM O. OWEN, Jr., of Lynchburg in the county of Campbell and State of Virginia, have invented certain new and useful Improvements in Rotary Steam-Engines; and I do hereby declare the following to be a full, clear, and exact description thereof, reference being had to the accompanying drawings, and to the letters of reference marked thereon, which form part of this specification, in which—

Figure 1 is a front or side elevation of my improved rotary engine with the front plate removed. Fig. 2 is a central vertical section 15 of the engine complete. Fig. 3 is a face view of the body-plate; Fig. 4, a similar view of the cam-grooved plate. Fig. 5 is a horizontal section of the engine. Fig. 6 is a sectional detail of the valve. Fig. 7 is a horizontal section of the cut-off; Fig. 8, a transverse section 20 of the same; Fig. 9, a perspective of the cut-off guard.

The invention relates to improvements in rotary steam-engines, and its object is to provide a reversible engine of simple and cheap construction in which the expansive force of the steam can be utilized.

The invention consists in the construction and novel arrangement of parts hereinafter explained, and pointed out in the appended claims.

Referring to the accompanying drawings by letter, A designates the case of the engine, of cylindrical form and standing on the base A', which is bolted or otherwise secured to a proper supporting-bed. The case A is composed of the body portion A² and the circular front plate, A³, bolted thereon. The body portion A² has a central opening, a, through which the 35 main shaft passes, a similar opening, a', being made in the plate A³ for the same purpose.

A⁴ is a circular chamber made on the inside of the body portion A² by the wide circular flange a², which stands therefrom, and is concentric with the shaft. When the plate A³ is bolted on, the chamber A⁴ is closed, and is packed steam-tight.

B is the main shaft rotating centrally in the case and passing through stuffing-boxes on 45 the front plate thereof.

B' is a disk secured on the shaft concentric

therewith within the chamber A⁴. The disk B' fits accurately against the sides of the chamber A⁴, and forms within said chamber the steam-space B², concentric with the shaft. 55 The disk B' is made steam-tight by any proper packing.

B³ is the piston-block secured upon the circumference of the disk B', and more fully described hereinafter.

The engine may have several abutments, but it is preferable to have two only. If there are more than two, they are duplications of each other, and the description of one only is necessary.

C is one of the abutments of rectangular form and moving in the radial recess c, made in the flange a² of the casing. From the edge of the abutment adjacent to the side of the body portion A² of the casing stands out at 70 right angles the steel pin c', having on its end the steel or case-hardened friction-roller c². The pin passes through a radial slot, c³, in the wall of the body portion A² of the casing, and enters a cam-groove, c⁴, in the plate C', fixed 75 on the main shaft and rotating therewith in juxtaposition with the casing. This cam-groove c⁴ is made with one portion, X, concentric with the shaft for a distance of a little more than one hundred and eighty degrees— 80 say one hundred and eighty-five degrees. Another portion, X', of the cam-groove is concentric with the shaft on the arc of a larger circle for from twenty to forty degrees. The radial difference between the circles on which 85 the portions X X' are made is equal to the width of the steam-space B². The parts X X' are connected on each side by the eccentric parts x x.

The main shaft B turns in bearings D D, 90 made on standards D' D', which rise from the bed or base of the machine. The end of the main shaft outside of the bearings D has secured upon it a toothed collar, E, which forms one half of a clutch, E, the other half being 95 formed by a similar and engaging collar, E², which is splined upon a shaft, B⁴, aligned with the main shaft B, and carrying the pulleys for transmitting power to the mechanism to be actuated.

The shaft B is provided with the central channels, F F', which have the radial continu-

ing channels $f'f''$, opening upon the circumference thereof. The channels $f'f''$, respectively, meet and continue the channels $G'G''$, which run radially through the piston-block B^3 and the disk B' , and open on opposite sides of the piston-block by means of the transverse channels $g'g''$, respectively.

G^2G^3 are grooves made from the outer ends of the channels $G'G''$ along the top and sides of the piston-block, and intended to receive steam and pack the piston-block therewith to prevent friction. The piston-block may, if desired, be packed in the ordinary manner. The channels $F'F''$ open at their outer ends upon the circumference of the shaft through the channels $H'H''$, respectively.

$I'I'$ are cylindrical steam-cases, which surround the shaft over the openings of the channels $H'H''$, respectively, the shaft passing through stuffing-boxes in the ends of said cases. From the cases $I'I'$ run the pipes $h'h'$ to the valve-chest J , which is provided with the exhaust-port K , situated between the openings $k'k'$ of the pipes $h'h'$. The valve-chest is connected with the boiler by a steam-pipe, L , controlled by a proper throttle-valve, and has on its interior a slide, M , which is controlled by the pivoted lever-handle M' , and is arranged to direct the steam through either pipe h or h' . When the steam is admitted by the pipe h , it exhausts through the pipe h' , and when admitted through pipe h' it exhausts through h . Each steam-case $I'I'$ has on its interior a cut-off tube, N , which fits over the main shaft, and can be moved longitudinally by means of a rod, n , parallel with the shaft and passing through a stuffing-box on the outer end of the casing. The rod N is provided with a proper handle outside of the case, and is graduated so that it can be accurately set to cut off the desired amount of steam.

The inner end of the cut-off tube N is beveled or inclined, so that it will lie more or less over the path of the rotating mouth of the channel H or H' , according as the tube is moved inward or outward. If the engine has two abutments, each cut-off tube has two similar and opposite bevels. The number of bevels of the cut-off tubes is equal to the number of abutments with which the engine is provided.

The method of operating the engine is as follows: If it is desired to run the engine by a continuous steam-pressure, both cut-off tubes N are slid back, so that the openings of the bores $F'F''$ in the main shaft are uncovered during the entire revolution of the same. The connection of the pipes $h'h'$ with the valve-chest enables the engineer to reverse the engine at will.

To work the engine by expansion, the tube N on the side toward which the engine is exhausting is slid entirely back, and the cut-off tube on the steam-receiving side is set in proper position to receive steam during the

desired part of the rotation of the shaft. The steam can thus be admitted during the whole rotation of the main shaft or during any part of the same, the rod n gaging the extent of slide of the cut-off N .

The formation of the cam-groove c^4 causes one abutment to close just as the piston-block has passed it and the other abutment to open, the interior steam-pressure aiding in sliding out the opening abutment.

Having described my invention, I claim—

1. In a rotary steam engine, the combination of the main shaft having the steam and exhaust channels made longitudinally therein, and the cut-off tubes surrounding the main shaft and adapted to be adjusted at different positions upon the openings of the steam and exhaust channels of the main shaft, substantially as specified.

2. In a rotary steam-engine, the combination of the shaft having the steam and exhaust channels made therein, the steam-cases surrounding the openings of said channels, and the cut-off tubes having the ends beveled, as described.

3. In a rotary steam-engine, the combination of the shaft having the steam-exhaust channels made therein, the steam-cases surrounding the port of said channels, the cut-off tubes with beveled ends, the steam-pipes running from the steam-cases to the valve-chest, and the valve-chest adapted to reverse the engine, substantially as specified.

4. In a rotary steam-engine, the combination of the casing having the steam-chamber formed therein, the shaft provided with steam and exhaust channels, the disk secured to and rotating with the shaft, and the piston-block secured to the disk and provided with steam and exhaust ports, substantially as specified.

5. In a rotary steam-engine, the combination of the main casing having the steam-space formed therein, the shaft, the disk and piston-block rotating with the shaft, the abutment-blocks provided with the steel pins, which pass through radial slots in the casing, and the cam-grooved disk, which is secured to the shaft and actuates the abutment-blocks substantially as specified.

6. In a rotary steam-engine, the combination of the cylindrical main casing, the shaft receiving steam and exhausting through its axis, the disk and piston-block rotating with the shaft, the abutment-blocks provided with steel pins passing through radial slots in the main casing, and the cam-grooved disk secured to the shaft and actuating the abutment-blocks, substantially as specified.

In testimony that I claim the foregoing as my own I affix my signature in presence of two witnesses.

W. O. OWEN, JR.
